PORTABLE RADIO OR THE LIKE

Sam Jack Phillips, New York, N.Y., assignor to Inter-Ocean Electronic Corporation, New York, N.Y.

Filed Sept. 15, 1964, Ser. No. 81,731

Term of patent 3½ years

(Cl. D56—4)

FIG. 1

FIG. 2

FIG. 3

FIG. 1 is a front elevational view of a portable radio or the like, showing my new design;

FIG. 2 is a top plan view of the same; and

FIG. 3 is an elevational view of one side thereof.

The bottom, rear and side not shown are substantially plain and unornamented.

I claim:

The ornamental design for a portable radio or the like, substantially as shown and described.
